UNITED STATES PATENT OFFICE

2,302,500

EDUCATIONAL DEVICE

Stewart D. Long, Chicago, Ill.

Application January 21, 1942, Serial No. 427,645

1 Claim. (Cl. 35—52)

This invention relates to an educational device to be employed as a toy for the self-education of children and adults alike, also may be utilized for demonstration purposes to create interest of onlookers.

The primary object of this invention is the provision of a portable device which may be readily set up for use either by a child or adult and includes, besides a case designed to be representative of the interior of a building or factory when opened, an assembly conveyor and the various parts of article of manufacture, such as automobiles or other types of vehicles with the parts segregated and readily accessible, so that said child or adult by placing together the parts of the vehicle on the assembly conveyor will become thoroughly familiar with the construction and the operation of the vehicle, consequently permitting the child or adult to be self-educated as well as amused, also when the device is employed for demonstration purposes, onlookers will be kept interested thereby and receive education.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a top plan view, partly broken away, showing the case of the invention and other various units.

Figure 2 is a sectional view taken on the line 2—2 of Figure 1.

Figure 3 is a fragmentary vertical sectional view illustrating a portion of the assembly conveyor with an assembled article of manufacture thereon.

Figure 4 is a transverse sectional view of the assembly conveyor.

Figure 5 is a top plan view partly in section showing the device arranged for use.

Figure 6 is a side elevation of part of the case or the cover thereof arranged in open position and showing its interior face designed to be representative of wall construction of a building or factory.

Referring in detail to the drawings, the numeral 5 indicates a case including a removable cover 6, the interior face of which is representative of a wall construction of a building or factory.

While the case 5 is portable so that it may be

conveniently carried or moved from one place to another it has an interior area sufficient for the accommodation of an assembly conveyor 8 and a plurality of boxes or containers 9 for the keeping of various parts of articles of manufacture assembled, also the case makes provision for the accommodation of large size parts used in the assembly of the articles of manufacture.

The assembly conveyor 8 includes a channeled frame construction 10 in which are journaled adjacent the ends thereof rollers 11 for the support of an endless belt 12, the upper run of which is employed for the movable support of articles of manufacture as the various parts thereof are assembled together. A small size power medium 13 in the form of an electric motor or the like is suitably mounted in the frame construction 10 and drives a roller 14 engageable with the endless belt or the lower run thereof as it moves off of one of the rollers 11. One end of the supporting structure 10 is inclined to form a ramp 15 at one end of the assembly conveyor so that the articles of manufacture may gravitate therefrom when reaching the end of the conveyor.

If desired, the frame structure 10 may be made to adjust lengthwise so that it can be lengthened and shortened for use and for storage within the case. This can be easily accomplished by having the frame construction 10 composed of telescopic sections.

The containers 9 are each labeled or marked in some suitable way to designate the parts of the articles of manufacture such as automobiles or other vehicles kept therein. Large units of the articles of manufacture may be stored in the area of the case not employed for the containers 9 and the assembly conveyor. A clear illustration of the foregoing will be seen from Figure 1.

For a child or adult to be amused and receive education from this invention the case is arranged on a table or some other suitable support and the cover placed vertically so as to give the appearance of an interior wall construction of a building or factory. The endless belt of the assembly conveyor is set in motion and the child or adult starting at one end of the belt places thereon the basic unit of the article of manufacture such as the chassis or frame, and as this unit progresses with the endless belt the child or adult applies thereto the other units which go to make up the complete article of manufacture so that on its arrival at the ramp 15 the article of manufacture will be completely assembled, consequently giving the child or adult a complete knowledge of all of the parts or units which go to make up

the article of manufacture and how they are assembled and coact with each other.

Therefore, it will be seen that the child or adult can obtain a thorough knowledge of this article of manufacture and at the same time be kept highly amused. Further it will be seen that this device can be economically manufactured and sold at a low cost, due to the fact that the assembly conveyor, case and various units of the articles of manufacture are constructed on a small scale and of inexpensive material.

When the device is used for demonstration or advertising purposes an instructor carries out the assembling of the articles of manufacture on the assembly conveyor as specified in connection with the child or adult so that onlookers will be kept amused and at the same time receive education as to the particular articles of manufacture.

While I have shown and described the preferred embodiment of my invention, it will be understood that minor changes in construction, combination and arrangement of parts may be made without departing from the spirit and scope of the invention as claimed.

Having thus described the invention, what I claim is:

In an educational toy, a substantially rectangular shaped portable supporting case including vertical side and end walls and a bottom wall, an elongated hollow frame structure located in the case on the bottom wall and close to one of the vertical side walls and having a downwardly inclined portion at one end thereof and provided with a horizontally disposed top wall, an endless power driven belt having one run movable over the top wall, rollers journaled on the elongated structure and having the belt trained thereover, a power driven roller journaled on the elongated structure and located adjacent one of the first-named rollers and bearing against the belt to force the latter tightly against the last-named roller, and a plurality of containers grouped in the case between the elongated structure and one of the side walls and the end walls and having therein parts of toy devices to be assembled with the belt acting as a movable support for said devices when partly and fully assembled.

STEWART D. LONG.
